UNITED STATES PATENT OFFICE.

GEORGE R. HEBDEN, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

SWITCH BOX.

Application filed September 23, 1925. Serial No. 58,050.

The main object of my invention is to provide a simple, inexpensive hinge which is rugged and reliable.

Another object is to provide a hinge which 5 may be readily attached after the box and cover have been electroplated, enamelled or otherwise finished.

Another object is to provide a separately 10 formed hinge by which practically all the strains are taken up by the hinge independently of the rivet or other means of securing the hinge in place.

Another object is to provide an entirely 15 pre-formed hinge member which may be readily secured in position by a simple rivet or other means in such a way that the surface finish of the parts is not marred or disfigured.

Fig. 1 is a perspective view of one end of 20 a box with a hinge embodying my invention, the cover being closed.

Fig. 2 is a side view and section showing the cover open.

Fig. 3 is a perspective view of one corner 25 of the box body, the cover being omitted.

Fig. 4 is a perspective view of one hinge member before attachment.

Fig. 5 is a perspective view of one corner 30 of the cover before attachment.

Fig. 6 is a sectional view of one corner showing the cover closed.

Such constructions are usually of sheet 35 metal and the covers of the boxes are usually provided with flanges which overlap the open sides of the box body 7 and fit the same more or less snugly.

The cover 8 is slotted at 11 to receive one 40 end of a hinge strap 9 and also to form a hinge pintle 16 which cooperates with the strap member 9 to form a hinge joint.

The box member is slotted at 10 to receive the end 12 of the hinge member 9.

The hinge member 9 is preferably pre-formed and is adapted to be inserted through 45 the slot 10 in the box and then turned so that one end 12 of the hinge member will hook against the inner wall of the box and the other end will lie flat against the outer wall of the box. During this assembling 50 operation, one end or the other, of hinge member 9 is inserted through the slot 11 in the cover so that, when the hinge member is turned to its final position, the pintle 16 of the cover is enclosed by the loop or arched

portion of the hinge member. When the 55 parts are in this position, the hinge member may be secured to the box by means of the rivet 15 or other suitable means.

It is particularly noted that, in this construction, there is practically no strain upon 60 the rivet 15. When the cover is opened to the straining point, the lower outside part of the hinge member is clamped between the flange of the cover and the outside wall of the box thus obviating any strain whatever 65 upon the rivet member 15 or whatever other form of securing means is employed. If, during the closing movement, the cover should become jammed in any manner so as to form a leverage upon the hinge, the 70 strain would be taken up by the arched portion of the hinge member 9 bearing upon the edge of the slot 10 in the box. Thus it is clear that the means for securing the hinge member in position might be a rivet 15 (as 75 shown) or it might be a hollow rivet, a split rivet, a thin metal eyelet, a screw or a spot welded point. In fact, the securing means is so free from any normal strain that a common pin or a small brad would be strong 80 enough for the purpose. This construction provides an easily applied, cheap and practical means for hinging such a cover to a box. It is a very neat construction and the hinge joint possesses the maximum strength. 85

The hinge members are preferably made from strip stock and, by simple shearing, piercing and forming operations, are pre-formed and completed before they are inserted into final position. Obviously the 90 slots in the box and cover members are registered and proportioned to cooperate properly with the hinge member.

A further great advantage is that the box, 95 cover and hinge members may be separately and completely plated, painted, enamelled or otherwise finished before they are assembled and the assembling can then be accomplished without in any way marring or injuring the surface or finish of the parts. 100

I claim:

1. A hinge construction including a rectangular box having a hinge slot, a cover for said box having a hinge slot in register with the hinge slot in the box and having an integral hinge pintle adjacent the hinge slot, an entirely pre-formed hinge strap having one end passing through the respective hinge 105

slots and having an abruptly bent end portion in flat engagement with the inner wall of the box, an arched portion engaging the said pintle and an outer end portion in flat engagement with the outer wall of said box together with means for securing the outer end of said hinge strap in position.

2. A hinge construction including a box and a cover therefor, said box and cover having registering hinge slots and said cover having an integral hinge pintle adjacent the hinge slot, a pre-formed hinge strap having an abruptly bent end portion in flat interlocking engagement with the inner wall of said box, a portion passing through the respective hinge slots, an arched portion partially surrounding said pintle and a flat end portion secured against the outer wall of said box, the box engaging end portions of said hinge strap being formed in parallel planes spaced apart the thickness of the wall of said box.

3. A hinge construction including a box having a hinge slot, a cover for said box having a hinge slot in register with the slot in said box and an integral pintle adjacent said slot, a pre-formed hinge strap having two offset flat box engaging end portions and an intermediate pintle engaging arched portion, one of said box engaging end portions

being passed through the respective hinge slots in the box and cover members and having an abruptly bent flat portion hooked against the outer edge of the inner wall of the box and the other end of said hinge strap being secured in flat engagement with the outer wall of said box and the arched portion of the said hinge strap securing the said pintle in position, the box wall engaging portions of said hinge strap being formed in parallel planes spaced apart the thickness of the wall of said box.

4. A hinge construction including a box having a hinge slot, a cover for said box and having a flange, said flange having a hinged slot in register with the slot in said cover and a hinge pintle adjacent said slot, a pre-formed hinge strap having box engaging flat end portions and an intermediate loop portion for engagement with said pintle together with means for securing said hinge strap in operative position with the surface of one of its end portions hooked in flat engagement with the inner wall of the box and the opposite surface of the other end of said strap in flat engagement with the outer wall of said box, the end portions of said hinge strap being formed in parallel planes spaced apart the thickness of the wall of said box.

GEORGE R. HEBDEN.
